US00D898447S

(12) **United States Design Patent** (10) **Patent No.:** **US D898,447 S**
(45) **Date of Patent:** **** Oct. 13, 2020**

(54) **CUSHION**

(71) Applicant: **Higher Auto Accessories Co., Ltd.**,
Sanmen (CN)

(72) Inventor: **Bin Xu**, Sanmen (CN)

(73) Assignee: **Higher Auto Accessories Co., Ltd.**,
Zhejiang (CN)

(**) Term: **15 Years**

(21) Appl. No.: **29/722,682**

(22) Filed: **Jan. 31, 2020**

(51) LOC (12) Cl. **06-09**

(52) U.S. Cl.

USPC **D6/601**

(58) **Field of Classification Search**

(74) Attorney, Agent, or Firm — Knobbe, Martens, Olson & Bear, LLP

(57) **CLAIM**

The ornamental design for a cushion, as shown and described.

DESCRIPTION

FIG. 1 is a top perspective view of a cushion according to our new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof; and,

FIG. 8 is a rear view thereof.

1 Claim, 8 Drawing Sheets
